CLAIM

The ornamental design for a mobile phone case, as shown and described.

DESCRIPTION

FIG. 1 is a top, front and right side perspective view of a mobile phone case showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded front, top, and right-side perspective view showing the components of the mobile phone case separated for clarity of disclosure.

For clarity of disclosure, the components of the mobile phone case are shown separated in FIG. 9. Although the mobile phone case, in which claimed design is embodied, consists of two separable components, the claim is directed to the overall ornamental appearance of the case in its entirety and does not extend to the ornamental appearance of each of the individual components in isolation.

The broken lines in the drawings illustrate portions of the mobile phone case or environmental subject matters which form no part of the claimed design.
